MUSICAL INSTRUMENT

Harlow B. Grow, Linden, Mo.

Application September 29, 1947, Serial No. 776,694

4 Claims. (Cl. 84—380)

1

This invention relates to wind instruments in general, and particularly to the kind which may be termed a bagpipe.

Bagpipes, in the sense known today, employ a mouthpiece or intake issuing into a wind bag which is held between the side and the arm for the purpose of compressing it. With the wind bag are connected several sound chambers and especially one provided with fingering holes for playing a melody, the other sound chambers serving to provide bass tones. In the bagpipe as presently used the wind bag must be compressed in order to supply air to the various sound chambers.

The present invention, while represented more or less as a toy, employs a different principle in that instead of a compressible wind bag, depending upon inflation and forceful compression, there is substituted a resilient, self-collapsing wind receptacle, adapted to automatically supply the necessary air under pressure to a sound chamber. The receptacle is inflatable through a relatively large passage provided in the mouthpiece, a check valve arrangement prevents air from re-entering the mouthpiece and escaping therethrough, thus forcing the air into a bleeder outlet which supplies air to the sound chamber. When sufficiently inflated the wind receptacle becomes gradually deflated as it delivers air under pressure into the sound chamber, such deflation being automatic due to the inherent, self-collapsing tendency of the resilient material employed in the production of the receptacle.

It is therefore the prime object of the present invention to provide a musical wind instrument wherein between its air intake and its outlet there is interposed a wind receptacle of highly resilient material which is intended to be inflated through the intake and which is adapted to deliver compressed air to the outlet or the sound chamber, such delivery of air to the latter being caused by the resiliency and the tendency of the receptacle material to collapse and to revert to its deflated form.

A further object of this invention is to provide a toy bagpipe of a relatively inexpensive and simple construction consisting of a mouthpiece and a sound chamber, and between which two elements there is interposed an air directing member provided with a relatively wide air supplying passage connected with the mouthpiece and a relatively narrow air delivering passage connected with the sound chamber, and which two passages issue into and are connected with one another by a resilient air receptacle made of

2

resilient material, such as rubber or any other resilient plastic which is capable of being inflated through the mouthpiece and deflated by its own resiliency while delivering air through and to without the sound chamber.

The foregoing and still further objects of the present invention will become more fully apparent from the ensuing description, in connection with the accompanying drawings, wherein:

- 10 Fig. 1 is a side elevation of the device with the air receptacle removed;
- Fig. 2 is a plan view thereof with portions of the device in section and showing a resilient air receptacle in the form of a balloon; and
- 15 Fig. 3 is a section taken on lines 3—3 of Fig. 2.
- Referring now specifically to the figures, numeral 10 denotes a mouthpiece, while numeral 11 indicates the sound chamber of the device. The latter, for example, comprises an elongated pipe open at its lowermost end and having a sound producing cut-out 12 and a plurality of tone-changing fingering holes 13. Interposed between mouthpiece 10 and sound chamber 11 is a bar portion of a substantially T-shaped air directing or air passage member 14 having a side extension or stem 15 in which is provided a relatively wide air passage 16 and a relatively narrow or bleeder passage 17. The side extension is enlarged at its end as at 18 to provide an attaching seat for the mouth 19 of balloon 20, shown in its inflated state. Mouth 19 of the balloon is preferably removably attached at the flanged or enlarged end 18 of extension 15, as for instance by means of a rubber band 19'. The enlarged end of extension 15 is recessed at 21 and in the recess there is housed a one-way check valve 22 secured at 23 and normally sealing the outer end of passage 16. The interior end of passage 16 connects with mouthpiece 10 while the interior end of narrow or bleeder passage 17 issues into the sound producing end of chamber 11. The outer ends of both passages 16 and 17 terminate at the face of recess 21, balloon 20 thus serving as connector of the two air passages.
- 20 Valve 22 opens under force of air pressure directed through mouthpiece 10 into the balloon but automatically closes when pressure ceases, whereby air is prevented from re-entering the mouthpiece and is directed into bleeder passage 17.
- 25 Fig. 3 shows the device in its inflated state. The balloon 20 is shown in its inflated state. Mouth 19 of the balloon is preferably removably attached at the flanged or enlarged end 18 of extension 15, as for instance by means of a rubber band 19'. The enlarged end of extension 15 is recessed at 21 and in the recess there is housed a one-way check valve 22 secured at 23 and normally sealing the outer end of passage 16. The interior end of passage 16 connects with mouthpiece 10 while the interior end of narrow or bleeder passage 17 issues into the sound producing end of chamber 11. The outer ends of both passages 16 and 17 terminate at the face of recess 21, balloon 20 thus serving as connector of the two air passages.
- 30 Valve 22 opens under force of air pressure directed through mouthpiece 10 into the balloon but automatically closes when pressure ceases, whereby air is prevented from re-entering the mouthpiece and is directed into bleeder passage 17.
- 35 Fig. 3 shows the device in its inflated state. The balloon 20 is shown in its inflated state. Mouth 19 of the balloon is preferably removably attached at the flanged or enlarged end 18 of extension 15, as for instance by means of a rubber band 19'. The enlarged end of extension 15 is recessed at 21 and in the recess there is housed a one-way check valve 22 secured at 23 and normally sealing the outer end of passage 16. The interior end of passage 16 connects with mouthpiece 10 while the interior end of narrow or bleeder passage 17 issues into the sound producing end of chamber 11. The outer ends of both passages 16 and 17 terminate at the face of recess 21, balloon 20 thus serving as connector of the two air passages.
- 40 Valve 22 opens under force of air pressure directed through mouthpiece 10 into the balloon but automatically closes when pressure ceases, whereby air is prevented from re-entering the mouthpiece and is directed into bleeder passage 17.
- 45 Valve 22 opens under force of air pressure directed through mouthpiece 10 into the balloon but automatically closes when pressure ceases, whereby air is prevented from re-entering the mouthpiece and is directed into bleeder passage 17.
- 50 As seen from Fig. 3, the difference in size between the wider passage 16 and bleeder passage 17 is substantial. Due to the relatively large dimension of passage 16 the inflation of the balloon is simple, easy and relatively quick. Inas-

much as the diameter of passage 17 is substantially smaller, the flow of air from the balloon into and out of sound chamber 11 is relatively slow and gradual as the balloon becomes deflated due to its tendency of self-collapsing. Thus the air retained in the balloon and supplied to the sound chamber will last for a considerable time sufficient to allow playing of a melody by covering and uncovering the different fingering apertures 13. The resiliency of the balloon material and the resulting self-collapsing tendency of the balloon, obviates the requirement of forcibly compressing the balloon to supply air to the sound chamber, as is the case in a bagpipe.

Referring again to Fig. 3, air outlet passage 17 terminates above an air directing block 23 inserted in the upper end of pipe 11. End face 24 of the block is flush with cut 25 of cut-out 12. The air thus passing through passage 17 over the inclined face 26 of block 23 is forced against the keen edge 27 produced by the slanting portion of cut-out 12 in pipe 11.

As indicated in Figures 1 and 2, the mouthpiece, the sound chamber as well as interposed member 14 are preferably made of substantially rigid material such as plastic, although they may be made of any other suitable matter such as wood or metal.

Obviously sound producing chamber 11 may be substituted by any other suitable sound producing structure, and by the same token the entire construction of the device may be altered to meet different requirements, all without departing from the scope of the present invention as presented in the annexed claims.

I claim:

1. In a toy bagpipe, a mouthpiece, a sound chamber fixedly associated therewith and forming a continuation thereof, a substantially T-shaped member interposed with its bar portion between the mouthpiece and the sound chamber, the stem or side extension of that member having a relatively large passage forming a continuation of said mouthpiece, and another, substantially smaller passage leading into said sound chamber, a resilient, inflatable element secured to said side extension for connecting said passages of the interposed member, and a check valve for said large passage adapted to prevent air from flowing from the inflatable element back into the mouthpiece, thus causing a flow of air under pressure through the smaller passage into the sound chamber.

2. In a wind instrument having a mouthpiece and a sound chamber, a substantially T-shaped air conveying member interposed with its bar portion between the mouthpiece and the sound chamber, its side extension having a relatively wide air passage connected at one end with the mouthpiece and a relatively narrow air passage issuing at one end into the sound chamber, a resilient, inflatable, self-collapsing balloon associated with the side extension of said member so that it connects the other ends of the passages, and a one-way check valve opening into the balloon normally closing the other end of the wide air passage.

3. In a wind instrument, the combination with a mouthpiece and a sound chamber, of an air conveying member having a side extension interposed between said mouthpiece and the sound chamber and having a relatively wide air passage and a relatively narrow bleeder passage, the side extension of said member having an enlarged end provided with a recess, a one-way check valve disposed in said recess and normally sealing the outer end of the wide passage, and a balloon removably attached to the enlarged end of the side extension and serving as connector for the two passages.

4. In a wind instrument, the combination with a rigid mouthpiece and a rigid sound chamber, of a rigid air conveying member having a rigid side extension interposed between said mouthpiece and said sound chamber, said side extension having an enlarged end with a recess therein, a relatively wide and a relatively narrow air passage provided in said member, both passages terminating in said recess, a one-way check valve in said recess and cooperating with said wide air passage, and a toy balloon removably associated with said enlarged end of the side extension.
